UNITED STATES PATENT OFFICE.

GOTTFRIED WELGER, OF SEEHAUSEN, GERMANY.

APPARATUS FOR BALING LOOSE MATERIALS.

1,409,128.

Specification of Letters Patent.

Patented Mar. 7, 1922.

Application filed August 5, 1920. Serial No. 401,452.

To all whom it may concern:

Be it known that I, GOTTFRIED WELGER, manufacturer, residing at Seehausen, district Wanzleben, Republic of Germany, have 5 invented certain new and useful Improvements in the Apparatus for Baling Loose Material, of which the following is a specification.

My invention relates to improvements in 10 apparatus for baling loose material and more particularly material the particles of which are very short such as chaff. When baling such material the bales must be bordered at their sides by cleats or boards in 15 order to have sufficiently coherent bales. The object of the improvements is to provide an apparatus for making bales which are coherent when leaving the press and which can conveniently be bound after being baled. With this object in view my 20 invention consists in constructing the partitions to be placed between successive bales in superposed sections each of which is designed to be bound to and border one of the 25 adjacent bales, and which are provided with suitable grooves or passages permitting the insertion of a binding element therethrough.

In the preferred form the said sections 30 are provided with connecting means of such construction as to maintain the proper relative position of the sections and alignment of the said grooves during the baling and binding operation and to allow the said sections readily to separate after binding.

35 In order that my invention may be more clearly understood the preferred forms of apparatus embodying the same have been shown in the accompanying drawing, in which the same letters of reference have 40 been used in all the views to indicate corresponding parts. In said drawing,

Fig. 1, is an end elevation of a partition,

Fig. 2, is a plan view thereof,

45 Figure 3 is a cross section of a modified form of my invention.

Figures 4-8 are end elevations of further modifications of the invention.

Fig. 9, is a plan view of a modified form.

50 Figure 10 is a top plan view of the form of my invention illustrated in Figure 9, parts being shown in section.

In the example shown in Figs. 1 and 2, the partitions consist each of two sectional plates *a* and *b* each of which is provided 55 with two transverse grooves *c* disposed in

such a way that in the assembled position of the sections corresponding grooves are in register with each other so as to provide between the sections a single passage.

As shown the grooves are provided by 60 cutting or fraising the same from the body of each section. The section *a* is provided with pins *d* preferably disposed at diametrically opposite corners and fitting in corresponding sockets *e* of the section *b*, 65 whereby a loose joint is provided between the sections.

In baling the sections *a* and *b* are placed upon each other in such a way that corresponding grooves *c* form a single passage 70 and that the pins *d* fit in the sockets *e*. The assembled partition is put into the baling press. After baling suitable binding elements are passed through the passages provided by the grooves *c* and around the 75 adjacent bales, whereupon the bales can be taken apart, the sections of the partitions remaining each on one side of a separate bale.

In the modification shown in Fig. 3 the 80 sections *a*¹ and *b*¹ consist of metal plates having the grooves *c*¹ formed therein by pressing.

In Fig. 4 I have shown a modification in which the grooves *c*² are provided on cleats 85 *d*² secured respectively to the sections *a*² and *b*². The pins *d*² and sockets *e* are provided on the cleats.

For binding the bales the binding elements for adjacent bales must be passed 90 through the same passages. Therefore, it may happen, that the ends of the two binding elements are erroneously changed, or that the said elements are entangled within their passages. Therefore I prefer to divide 95 each passage into two separate passages by means of a partition *f*³, as is shown in Fig. 5. In the example shown in Fig. 5 the

grooves *g*³, *h*³ are formed in the outer plates *a*³ and *b*³. In Fig. 6, the grooves *g*⁴, *h*⁴ 100 are shown in the partition *f*⁴, and in Fig. 7 the grooves *g*⁵, *h*⁵ are shown in the partition *f*⁵ as well as in the outer plates *a*⁵ and *b*⁵. In these examples the pin and socket connections are provided between the parti- 105 tions and both outer plates.

Where a strong and durable partition is desired I prefer the construction shown in Figs. 8, 9 and 10, in which the partition is made of a metal plate *i*⁶. The outer plates 110

- a^6 and b^6 consist of unfinished boards and are therefore not expensive. In Fig. 8 the grooves g^6 , h^6 are made in the partition boards f^6 .
- 5 In some cases I provide a plurality of narrow boards k^6 (see Figures 9 and 10) instead of single broad plates, which boards are preferably fitted in corresponding cut-out portions m^6 of the partition f^6 .
- 10 The method of baling consists in placing the combined partitions a , $b-a^1$, b^1-a^3 , f^3 , b^3 , etc., into the trunk wherein the material is being baled. After the material has been compressed bands are passed through the 15 passages c , g^3 , h^3 , etc., by means of which the sections of the partitions are tied each to separate bales, and when taking the bales apart, each bale is bordered at its front and rear ends by the sections a and b respectively. Where a partition f^3 , f^4 , f^5 , or f^6 is 20 used the said partition drops from the bales, so that it can directly be used again.

I claim:

1. As an article of manufacture a partition for baling presses comprising super-

posed sectional plates jointed by loose connections.

2. As an article of manufacture a partition for baling presses comprising super- 30 posed sectional plates formed with trans- verse grooves, and a partition adapted to be inserted between said plates during the pressing operation and subsequently released from the finished bales.

3. As an article of manufacture a parti- 35 tion for baling presses comprising super- posed sectional plates formed with trans- verse grooves, and jointed by loose connec- tions.

4. As an article of manufacture a parti- 40 tion for baling presses comprising three superposed sectional plates jointed by loose connections.

In testimony whereof I have affixed my signature in presence of two witnesses.

GOTTFRIED WELGER.

Witnesses:

OTTO LEMKE,
ARTHUR BEHROWS.
